(57) **CLAIM**

The ornamental design for a cable spacer support bracket, as shown and described.

DESCRIPTION

FIG. 1 is a perspective view of a cable spacer support bracket showing my new design;

FIG. 2 is a perspective view thereof with the cable spacer support bracket flipped 180° from that shown in FIG. 1;

FIG. 3 is a right side elevational view thereof with the left side being a mirror image thereof;

FIG. 4 is a front elevational view thereof;

FIG. 5 is a rear elevational view thereof;

FIG. 6 is a bottom plan view thereof; and,

FIG. 7 is a top plan view thereof.
